UNITED STATES PATENT OFFICE.

JOSEPH I. CONKLIN, OF BROOKLYN, NEW YORK.

METHOD OF PROTECTING RAILWAY-TRAINS.

SPECIFICATION forming part of Letters Patent No. 416,713, dated December 10, 1889.

Application filed December 20, 1888. Serial No. 294,281. (No model.)

To all whom it may concern:

Be it known that I, JOSEPH I. CONKLIN, a citizen of the United States, residing at Brooklyn, in the county of Kings and State of New York, have invented certain new and useful Improvements in the Method of Protecting Railway-Trains; and I do hereby declare the following to be a full, clear, and exact description of the invention, such as will enable others skilled in the art to which it appertains to make and use the same.

The object of this invention is to prevent collisions on railway-lines from carelessness or inattention to duty on the part of those having charge of trains by placing a reliable check on their faithful performance of the tasks imposed on them by the established rules of the railway.

When from any cause a train stops on the line and another crashes into it, there is always great difficulty in placing the responsibility for the accident where it belongs. The flagman may assert that he went back the regulation distance, and it is almost impossible to prove the real fact that he did not go back at all. The train-conductor at present, except in daylight on a straight track, has no means of knowing whether or not his flagman is performing his duty, and therefore frequently the testimony of the former is of little avail. It is believed by many that this difficulty in tracing the cause of the accident occasions much disregard of the most obvious precautions to secure safety.

I propose by my invention to not only prevent such disregard of well-founded rules and regulations, but also to provide means of communicating at once with the office of the train-dispatcher and giving the number of the train, the location where it stopped, and notify the presence or absence of the flagman from his post both to the train-dispatcher and the conductor of the train, and at the same time preserve a daily record of the facts just as they occurred.

To these and other ends my invention consists in the peculiar method of signaling hereinafter fully described, and particularly pointed out in the claim.

In the drawings which form part of this specification, Figure 1 is a diagram, illustrating my invention in its simplest form as ap-

plied to a line of railway. Fig. 2 is a similar diagram, showing the register in connection with the signal-circuit. Fig. 3 is an elevation of a signal-box adapted to perform the necessary functions; and Fig. 4 represents a portion of the permanent record of the movements of the train-crew and the accompanying incidents of an accident occurring, for example, during the night.

In carrying my invention into effect I proceed as follows: I arrange along the line of railway an electrical circuit, which may conveniently be grounded at both ends after passing at one end through the train-dispatcher's office and through the instrument therein located, to be hereinafter described. The circuit A may be either a pole-line or an underground line, as its particular arrangement in this respect forms no part of the present invention. At suitable intervals along this circuit I lead the main line A through signal-boxes 2, 3, 4, 5, 6, 7, 8, 9, and 11, and so on. These boxes I prefer to arrange at a convenient distance apart—such as a quarter or half mile—all the way along the line of railway. The boxes will be furnished with locks all alike, and the purpose is to furnish keys for them to the authorized person among the train-crews—such as the conductor and the rear brakeman or flagman. Each box is numbered, as stated, and contains, first, a make-and-break mechanism B, of any suitable character, capable of transmitting the box signal or number over the line after the manner of a signal-wheel in a fire-alarm box or in a district-telegraph box, so that by operating a crank or pulling a lever a make-and-break wheel will be caused to revolve and thus open and close the line in the manner required to transmit the necessary signal-number; second, a back-stroke bell or sounder C, or other equivalent device capable of giving a visual or audible signal when operated; third, a back-contact key D, and, fourth, a switch E, adapted to cut the signal device C out of the main circuit.

Referring to Fig. 3, it will be seen that the circuit comes in, for instance, at the left, passes to the make-and-break wheel B, thence to the key D, thence to the tail of the switch-lever, and from one point of the switch it passes through the magnet of the signaling

device C, through this directly to line at the right, and a direct circuit is made from the other contact of the switch also to line direct. In the figure, when the switch-lever is thrown 5 to the left the signaling device C is in the general circuit, and when the switch-lever is thrown to the right the device C is cut out of circuit and there is practically no resistance in the box.

10 The boxes 2, 3, 4, &c., are all exactly alike, except in the number of makes and breaks on the wheels B, and this is necessary in order to give a distinguishing-signal over the line for each box, in order to carry out the 15 purpose of this invention. At the train-dispatcher's office the line passes through a Morse register R, or, instead of passing directly through the register, the line passes through a relay whose local circuit operates 20 the register, which will be the preferred form on lines of any considerable length, and for the purpose of this invention the direct and indirect application of the register are substantial equivalents of each other. After 25 passing through the relay or register, line goes to the main battery M and thence to earth. At the distant end of the line it is grounded in the usual manner. Thus arranged there is nominally a closed circuit 30 through the register and through each of the signal-boxes along the line of railway, and in the latter there is no resistance except the mere resistance of mechanical contacts.

It is desirable in making use of my invention 35 to have in the train-dispatcher's office a map for convenient inspection, containing information as to the precise location of each of the signal-boxes with reference to the line of railway, so that as soon as any particular 40 box sends in its signal-number a glance at the map will instantly indicate where the box is located.

45 The system being thus installed, its operation under various conditions will be as follows: In order to simplify the matter of signaling by the train-conductor, I propose to establish a special code for the purpose, and this code can be printed in convenient form for the pocket and will be carried by each of 50 the train-conductors and each of the brakemen, and the rules and regulations of the service can be also included in the code-book.

As an instance of the character of the code, I will give a few of the signals which may be 55 very frequently necessary to transmit to the train-dispatcher: "Train off the track"—repeat box-signal twice." "Engine disabled"—repeat box-signal three times." "Collision"—repeat box-signal first twice, then once," and 60 so on, and in this manner a great variety of signals may be systematically arranged, and their transmission will be accurately understood, so that the train-dispatcher may at once know the character of the cause of stop- 65 page of the train and can immediately apply the remedy instead of waiting until some, perhaps very distant, telegraph-office has

been reached by one of the train-men and a message sent, as is now the practice. If now a train—for instance, train No. 47—meets 70 with any accident which compels its stoppage—such as the derailment of part or all of the train—the train-conductor will go to the box nearest the front of the train, open it, and first throw the switch to cut in his 75 signaling device into the circuit, and if the circuit is all right the fact will be indicated by the immediate attraction of the armature of the electro-magnet of such signaling device. He then turns the crank or 80 pulls the lever, so that immediately the box-number is transmitted to the train-dispatcher's office, the register set in motion, and the box-number impressed on the tape of the register. This immediately calls the attention of the train-dispatcher, and on seeing the number he can immediately refer to the map at hand and instantly learn where the stoppage has taken place. The train-conductor next sends in his train-number by means of 85 the key D, by operating it first four times and then seven times, which thus gives four dots, a blank, and seven dots on the tape at the train-dispatcher's register, thereby telling the latter exactly what train has had the accident 90 happen to it. In the meantime the flagman, acting in accordance with the rules, goes back to the box nearest the rear of the train, and on reaching it opens and operates the crank or lever once, thus sending in the box-number 95 to the train-dispatcher's office and notifying the train-dispatcher of the fact that the flagman has attended to his duty, and the fact is recorded, so that there can never be any doubt raised in the face of this record, and, as 100 this signal must always follow the train-conductor's first signal, if it is absent from the tape it will make it certain that the flagman neglected his duty and did not send in his signal, as required. This signal will be distinguishable from the train-conductor's signal 105 because it is sent from a different box. If the flagman sends his signal in this manner, the conductor is made aware of the fact before he leaves his box by the taps on the signal-bell caused by the makes and breaks in 110 the circuit effected by the flagman, and, hearing these signals, he at once knows that the flagman has done his duty and that the train 115 is protected at the rear. He can then communicate the nature of the accident to the train-dispatcher by means of the code of signals, and, as all this can be accomplished in a few moments, it will in some cases prove of 120 great value and importance to let the train-dispatcher, or the superintendent, if necessary, know that a very serious accident has occurred, which may require the immediate presence of surgeons, or may require the immediate sending out of a wrecking-train or a 125 substitute engine, or any other requirement of the service, such as the contingencies of accidents on a railway give rise to. Furthermore, as it is the rule on many railways now 130

that the baggage-master or some other permanent employé on each train shall be competent to transmit and receive messages telegraphically if the occasions require it, such 5 person can be called to the box by the conductor and operate the key and send in any special message that may be desirable and receive the reply thereto from the train-dispatcher direct or from the superintendent of 10 the division, if such be desirable.

With such a system, if the rules are adhered to, it is impossible to have a collision occur from the rear, and like protection may be afforded in front of the train on a single-track railway by sending an additional flagman ahead with similar instructions; and if the rules are not adhered to by either the flagman or conductor the fact is brought directly home to him by the registered signals 15 on the tape which may be kept on file in the train-dispatcher's office. This will be more clearly observed by inspection of the history of one stoppage of a train, as indicated by Fig. 4, which is the complete record. It will 20 be observed that a signal has come in from box 24, which indicates at once that some train has stopped at a point in the neighborhood of box 24. The next signal is 31. This indicates that the stoppage occurred to train 25 No. 31, and as it is usual to designate trains bound in one direction by even numbers and trains bound in the other direction by odd numbers, the fact is made known as to the direction in which train No. 31 was proceeding 30 at the time it stopped. The next signal is found to be box No. 23, which indicates that the brakeman attended to his duty in the proper manner and that the train was protected at the rear. The next signal found 35 on the tape is the box No. 24 repeated three times. This at once indicates that the engine was in some manner disabled, and if any special information is sent in by means of the key D at the box 24 the fact will be recorded on the tape in regular Morse characters. The time at which the first signal came 40 in to the dispatcher's office in this record will be marked on the tape by the attendant in the office at the time the first signal comes, 45 so that we have thus a complete history of the entire occurrence. If now any question is raised as to whether or not either the conductor or flagman performed his duty at the proper time it can all be determined by inspection of the record. As an instance, suppose 50 a record comes in similar in all respects to that shown in Fig. 4, but now having on the tape the signal from box 23. It at once proves that the flagman neglected his duty, 55 and if an accident has occurred owing to such neglect the blame can be laid where it belongs—namely, on the flagman, who did not go back to the box nearest the rear of the train and send in his signal.

60 65 I wish to observe that while I have described the invention as a means of signaling

various points of information to the train-dispatcher's office, the recording of the signals in the train-dispatcher's office is for the purpose of preserving a record; but the essential 70 feature of my invention, which has for its purpose the protection of the train itself, will be found in the application to the line of railway of a closed electric circuit containing a battery and a number of signal-boxes along 75 the railway accessible to authorized employés on the train, each box containing not only the signal-transmitting device or make-and-break wheel, but also a signal-receiving device—such as a bell or sounder—and with 80 this equipment alone the train-conductor can determine whether or not the flagman has gone back to the box nearest the rear of the train and sent in the signal therefrom, so that he may thus become assured of 85 the safety of his train from the rear. In case the next box to the rear is too close to the train, it will be the duty of the flagman to also go to the next box back and signal also from it. I thus not alone secure the immediate 90 safety of the train, but by recording these signals at the train-dispatcher's office the various actions of the train-crew are plainly marked on the tape and can be readily preserved for reference at any future time. 95

Another function which can be fulfilled by the use of my invention will be the preservation of a check upon the track-walkers, whose duty, in accordance with my system, will be to open each of the signal-boxes as they come 100 to it, and send in the number of the box and an "O. K." signal, where such may be desirable.

To avoid danger from accidental grounding of the line at intermediate points, I prefer to 105 adopt the well-known alternative in systems of telegraphy and divide the battery M, placing half of it at each end, where there is usually a train-dispatcher's office, and also placing a register at each of such offices. In this 110 way, should a ground occur at the middle or any intermediate point of the line A, the remaining portions of the line are not disturbed, and the signals can be sent in to the train-dispatcher's office in which that particular 115 part of the line which is operated ends.

It is not important in sending in the signals from the conductor and flagman as to the particular order in which the signals follow each other, and I therefore do not confine 120 myself to any particular order, as this may be arranged to suit the taste of the superintendent of the telegraphic service.

After the damage has been repaired and the train is about to start again the conductor can, 125 by means of the key D, send a predetermined signal that everything is now all right and the train is starting. Such a signal I have indicated in Fig. 4 by three dots on the tape, which will correspond to three movements of 130 the key at the signal-box, and the attendant at the dispatcher's office receiving this signal

will immediately note the time, and thus the record will also contain information as to the length of the stop made by such train.

I claim as my invention—

- 5 The method of protecting railway-trains and recording the circumstance of their stopping, consisting in electrically signaling to the train-dispatcher's office the stoppage of a train from a point adjacent to the rear of the train, and indicating such signal at a point adjacent to the front of the train, then signaling the stoppage to the dispatcher's office from a point adjacent to the front of the train, then signal-

ing the train-number and designating symbols for the location of the stoppage, and automatically recording such signals at the train-dispatcher's office, whereby a permanent record is made of the stoppage, the train which was stopped, and the place it stopped.

In testimony whereof I affix my signature in presence of two witnesses.

JOSEPH I. CONKLIN.
